UNITED STATES PATENT OFFICE.

GEERT MOEKE, OF ZEELAND, MICHIGAN.

SILO.

942,095.

Specification of Letters Patent.

Patented Dec. 7, 1909.

Application filed April 2, 1909. Serial No. 487,450.

To all whom it may concern:

Be it known that I, GEERT MOEKE, a citizen of the United States of America, residing at Zeeland, in the county of Ottawa and State of Michigan, have invented certain new and useful Improvements in Silos; and I do hereby declare the following to be a full, clear, and exact description of the invention, such as will enable others skilled in the art to which it appertains to make and use the same.

My invention relates to improvements in silos, and more particularly to the doors and adjacent parts thereof, and its object is to provide the same with various new and useful features hereinafter more fully described and particularly pointed out in the claims, reference being had to the accompanying drawings, in which:

20 Figure 1. is a front elevation of a portion of a silo embodying my invention; Fig. 2. is a vertical section of the same on the line 2—2 of Fig. 1.; Fig. 3. is a horizontal section of the same on the line 3—3 of Fig. 1.; 25 Fig. 4. the same on the line 4—4 of Fig. 1.

Like numbers refer to like parts in all of the figures.

1 represents a portion of the body of the silo, preferably made of vertically disposed 30 staves joined to each other by tongue and groove at their edges. This structure is surrounded by hoops or bands 2, preferably of round rod provided with any convenient means of tightening the same (not shown).

35 The staves are spaced apart to form a door opening wherever convenient and across this opening at regular intervals corresponding to the intervals of the hoops or bands, are horizontal braces 3 having an outer surface 40 concentric with the axis of the structure and of somewhat greater radius to project outward therefrom a convenient distance, and in this outer surface is a deep groove 3^a to receive the respective band. These braces 45 overlap the adjacent staves at the outer side and are secured thereto by bolts 4 and between the staves the braces extend inward to the inner surface of the structure and are connected to the staves by tongues and 50 grooves 11 and 12, whereby the adjacent edges of the staves are securely held and connected to the braces, and the braces also held thereby.

55 The inner sides of the braces are preferably rectilinear and the braces are beveled inward to fit the beveled upward and lower

edges of the doors. The respective doors consist of a series of strips, preferably three as shown, but any number may be used, joined to each other with tongues and 60 grooves, and also joined to the adjacent staves in like manner, as at 11 and 12. These tongues and grooves are preferably semi-circular in cross section, whereby these strips will swing freely into and out of engagement upon hinges 6 connecting them to each other in series. The door is also hung to swing inwardly upon oppositely arranged hinges 6^a at one side of the opening and supporting the door upon an adjacent stave. 70 The middle strip is also provided with a fastening consisting of a cam inclined to the surface of the door and eccentrically pivoted at 9 to the same, and also adapted to swing into a recess in the under side of the brace 75 bar 3, by means of a lever 10, thus being protected from the weather by the overhanging brace bar and prevented from clogging by snow or ice. Each door is also provided with a horizontally disposed handle 7, which 80 is available to close the door and also useful in climbing upon the outside of the structure by means of these brace bars as foot holds.

What I claim is:

1. A silo, comprising staves spaced apart to form a door opening, braces at intervals across said opening, and doors between said braces, each consisting of a series of strips hinged to each other, said strips also joined 90 to each other and to the adjacent staves by tongues and grooves, and means for securing the doors in closed position between the braces and staves.

2. A silo, comprising vertically disposed 95 staves joined to each other by tongues and grooves and spaced apart to form a door opening, braces at intervals across said opening, and beveled at the upper and under sides to receive the doors, doors between the 100 braces, each consisting of three separate strips hinged to each other and one side strip hinged to the adjacent stave, said strips also being joined to each other and to the adjacent staves by detachable tongues 105 and grooves and a fastening and handle on the middle strip.

3. A silo, comprising vertically disposed staves joined by tongues and grooves and spaced apart to form a door opening, brace 110 bars at intervals across said opening and extending between adjacent staves and

joined thereto by tongues and grooves and also overlapping on the outside of said staves and bolted thereto, said braces also each having beveled upper and lower sides 5 and a groove in the outer side, bands surrounding the staves and extending through said grooves, doors between the braces, each consisting of a series of separate strips hinged to each other and joined to each

other and to the adjacent staves by tongues and grooves and beveled at the end to fit the braces.

In testimony whereof I affix my signature in presence of two witnesses.

GEERT MOEKE.
